US00D862493S

(12) **United States Design Patent** (10) **Patent No.:** **US D862,493 S**
Kaasalainen et al. (45) **Date of Patent:** **** Oct. 8, 2019**

(54) **DISPLAY SCREEN WITH GRAPHICAL USER INTERFACE**

(71) Applicant: **HMD Global Oy**, Espoo (FI)

(72) Inventors: **Janne Kaasalainen**, Espoo (FI); **Ari Pekka Liusaari**, Milan (IT); **Shahil Soni**, Espoo (FI); **Tero Tiittanen**, Espoo (FI); **Jung-Chen Hung**, Helsinki (FI)

(73) Assignee: **HMD Global Oy**, Espoo (FI)

(**) Term: **15 Years**

(21) Appl. No.: **29/619,802**

(22) Filed: **Oct. 2, 2017**

Related U.S. Application Data

(60) Continuation of application No. 29/568,613, filed on Jun. 20, 2016, now Pat. No. Des. 798,884, which is a division of application No. 29/457,258, filed on Jun. 7, 2013, now Pat. No. Des. 763,861.

(57) **CLAIM**

The ornamental design for a display screen with graphical user interface, as shown and described.

DESCRIPTION

The FIGURE is an image of a front view of a display screen with graphical user interface showing our new design. The broken line showing of the remainder of the user interface and display screen is for environmental purposes only and forms no part of the claimed design.

1 Claim, 1 Drawing Sheet
